CLAIM

The ornamental design for a mounted power station, as shown and described.

DESCRIPTION

FIG. 1 is a front, top and left side perspective view of a mounted power station showing my new design;

FIG. 2 is a front, bottom and left side perspective thereof;

FIG. 3 is a top plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a bottom plan view thereof;

FIG. 9 is a front, top and left side perspective view thereof, in use condition; and,

FIG. 10 is another front, top and left side perspective view thereof, in use condition.

The broken line shown in FIGS. 9 and 10 is for the purpose of illustrating unclaimed environment only and forms no part of the claimed design.
